OIL WELL PUMP

Filed April 23, 1926

UNITED STATES PATENT OFFICE

WILLIAM F. McMAHON, OF RIVERSIDE, CALIFORNIA

OIL-WELL PUMP

Application filed April 23, 1926. Serial No. 104,159.

This invention relates to oil well pumps, that is, pumps for raising oil from deposits within the earth. It is of the general type of pump and is used in practically the same 5 manner as the pump disclosed in my application Serial No. 104,158, filed April 23, 1926.

It is an object of the invention to provide a pump of this character which has clear fluid passageways so that sand or the like will not 10 interfere with the operation thereof.

It is also an object of the invention to provide a pump which will have sustained efficiency and will provide a steady flow of fluid from the well.

15 Another object of the invention is to provide a pump in which under normal operation there are no movable parts within the well, and therefore, replacement costs are reduced to a minimum.

20 A further object of the invention is to provide a pump which will be independent of gas pressure in the well.

A still further object of the invention is to 25 provide a pump system in which several oil wells at reasonable distances apart may be pumped by one power plant.

Another object is to provide a pumping apparatus in which all machinery with moving 30 parts is located above the ground where it can be looked after and easily inspected.

With the foregoing and other objects in view, I have devised the improved construction illustrated in the accompanying drawing forming a part of this specification, similar 35 reference characters being employed throughout the various figures to indicate corresponding elements. In this drawing,

Fig. 1 is a vertical section through an oil well, a portion of the derrick floor and base, 40 showing my improved pumping system applied thereto, a part of the pump proper being shown in elevation, and the remainder of the pump and the separating tank being shown in section.

45 Fig. 2 is a vertical section through the body member of the pump which is located in the well, the section being substantially on line 2-2 of Fig. 2.

50 Fig. 3 is a vertical section through the lower portion of this body member, the sec-

tion being at right angles to the section of Fig. 2, as indicated by line 3-3 of Fig. 7.

Fig. 4 is a transverse section through the conduits leading to the body member, the section being substantially on line 4-4 of 55 Fig. 2.

Figs. 5, 6 and 7 are cross sections of the body member taken substantially on lines 5-5, 6-6 and 7-7 respectively of Fig. 2, 60 and

Fig. 8 is a top plan and side elevation of one of the check valves.

In the drawing 10 represents the oil well which is a hole drilled from the surface of the earth to the oil deposit. After the oil 65 deposit is penetrated the pressure raises the column of oil to a certain level in the well which is indicated on the drawing at 11. It is into this column of oil that I lower the lower portion of my oil pump proper, and 70 which in the present instance is the body member 12, and this body member is connected with two concentric pipes 13 and 14 leading from the surface of the earth, the two pipes being spaced sufficiently to leave a passage for fluid between them. It should be noted that the oil well casing itself can be used 75 for pipe 14 if it is so desired.

As is well known the available space with 80 in the well is limited, and to economize in space the body 12 is preferably of a substantially cylindrical casting. When cast it is left open at its lower end for machining and assembling purposes, and when assembled this open end is closed by a closure 15 which 85 may also have a cleanout plug 16. Within the body is a longitudinally extending centrally located oil passage 17 at the upper part thereof which has a flared open lower end 18. While I have shown this open lower end 18 90 with a flared formation, it should be noted that this lower end 18 may be of any shape. Just above this flare the passage is preferably provided with a restriction 19 and again flared somewhat, as shown at 20, from this 95 restriction to the normal diameter of the passage. Below the inlet 18 is a nozzle member 21 which has a restriction 22 adjacent its upper end with flaring portions 23 and 24 above and below this restriction, the upper 100

flare opening through the end of the nozzle which is spaced a suitable distance below the flared inlet 18 and is directed to discharge into this inlet. The lower end of the nozzle communicates with the chamber 25 in the lower end of the body, and the body has spaced transverse walls 27 and 28 through which the nozzle extends and in which it is removably mounted, the walls being provided with threaded openings and the nozzle being correspondingly threaded on its outer wall, as indicated at 29 and 30 respectively. If desired a strainer means may be placed in chamber 25 to screen the entrance to the nozzle 21. Between the walls 27 and 28 the sides of the body are open except on one side and this opening is covered by a screen or strainer 31 secured to the body by any suitable means, such as screws 32, and thus the nozzle member 21 really passes through a chamber 33 which is open through the sides of the body and communicates through the screen or strainer with the well and the oil therein. The oil passage 17 is supported by a transverse wall 34 spaced above the wall 27 and also by radial walls 35 extending between the walls of this passage and the outer walls of the body, and thus the oil passage 17 is surrounded by the water passages 36 and 37. The water passage 36 extends throughout substantially the entire length of the body and communicates at its lower end with the lower chamber 25 while the passages 37 are closed at their lower ends by the transverse wall 34 but they communicate at their lower ends with the passage 36.

As the wall 34 is spaced from the wall 27 there is provided between them a suction or inlet chamber 38 surrounding the open lower end 18 of the oil passage 17, and the discharge end of the nozzle 21 is located in this chamber. The wall 27 is provided with curved oblong openings 39 extending through it forming communicating passages between the chamber 33 and the chamber 38 to allow passage of oil from the chamber 33 and the oil deposit to the chamber 38. These openings 39 are controlled by check or non-return valves 40 which have tapered lower walls 41 adapted to seat on correspondingly tapered walls forming valve seats at the upper side of the passages 39. The valves are guided for upward movement by suitable guide pins 42 and their upper movements are limited by stops 43.

The outer and inner concentric pipes 13 and 14 are connected to the upper part of the body 12, as indicated in Fig. 2, so that the inner pipe 13 leads to the oil passage 17 and the space or passage 44 between these two pipes communicates with the water passages or forcing fluid 36 and 37. At the surface of the earth the outer pipe 14 is connected by a curved elbow fitting 45 with the discharge 46 from a pump 47, preferably a

duplex, double acting, reciprocating pump which will deliver a substantially constant stream of water or other suitable fluid. The inner pipe 13 passes through a suitable stuffing box 48 in the fitting 45 and discharges through the curved section 49 into the separating tank 50.

This tank is of a sufficient capacity to retain the mixture of oil and liquid, such as water, for a sufficient time to allow the water to fall to the bottom of the tank and the oil to separate and float thereon, and it is provided with a valve controlled discharge 51 at its upper portion for the discharge of oil to a pipe line, for example. Leading from the lower part of the separating tank is a valve controlled pipe 52 leading to the inlet or suction pipe 53 of the pump 47, and in the tank over this discharge opening is an inclined screen 54 which is adapted to collect sand or other solid matter which may be deposited in the tank with the mixture of oil and fluid and will prevent passage of this solid matter to the pump 47. The tank may also be provided with a valve controlled cleanout passage 55 for removal of the solid matter from the tank. A pipe 56 is connected to the pipe 52 and leads from any suitable source of compressed air which may be used to agitate the liquid in the tank and clean the screen 54. There may also be a valve controlled supply 57 from any external source of water. The discharge pipe 46 of the pump 47 may also have branches 58 controlled by suitable valves, not shown, by which discharge from the pump may be conducted to other oil well pumps so that the same water or fluid pump may be used to operate a plurality of oil pumps. I wish to have noted at this time that while I have heretofore mentioned water as a motive fluid it is obvious that any kind of fluid may be used as a motive fluid and used to equally good advantage.

In operation the water or other fluid is pumped by the pump 47 in a continuous stream down the passage 44 between the two pipes 13 and 14 to the body member 12 in the oil deposit. This fluid passes down the passage 36 to the chamber 25 and up through the nozzle member 21 from which it passes through the restriction 22 and into the flared open inlet end of the oil passage 17. This restriction gives an increased speed of flow to the fluid which acts to lift oil from the suction chamber 38 into the passage 17 and the movement of the fluid up this passage carries the oil with it and it is discharged at the surface of the earth into the separating tank 50. After separation the water or other liquid is again drawn into the pump 47 and is used over and over. The lifting of the oil is also assisted by the fact that when water or similar liquid is used the oil is of a lower specific gravity and will, therefore, tend to float on the liquid and to move up the inner pipe 13.

to the surface. Of course, as oil is withdrawn from the chamber 38 other oil is drawn into this chamber from the deposit through the check valves 40 so that in normal operation these valves remain in the upper or open position and close only when the stream of pumped liquid ceases. They close by their own weight as soon as this flow stops, and therefore, prevent any water passing from the pump out into the oil deposit. This is a very important feature as flow of water into the deposit will stop the flow of oil. It should be noted however that when using a motive fluid other than water these said check valves 40 may be eliminated if desired and the pump will function equally as well.

The concentric arrangement of the supply and discharge pipes 13 and 14 requires a minimum of space for the same capacity in the well, cuts down the friction of the fluids in the pipes and gives larger areas in the same space for the flow of the liquids. It will be apparent that the passages are all free and clear so that sand in the oil is no obstacle. Also that with the exception of the check valves which have very little movement, all the movable parts or mechanism are located at the surface of the earth where they may be easily inspected and kept oiled and in repair.

Having thus set forth the nature of my invention, what I claim is:

1. In an oil well pump for raising oil from deposits in the earth, a body adapted to be placed in the deposit and having a substantially central longitudinally extending oil passage in the upper portion thereof provided with a flared open lower end, spaced cross walls in the body forming a chamber with which said lower end communicates, another cross wall spaced below the other walls forming a chamber opening through the side walls of the body, and a chamber below said wall, a separate nozzle extending through said two lower walls having a discharge end in the upper chamber directed into the open end of the oil passage and communicating at its lower end with the lower chamber, the intermediate cross wall having an opening forming a communication between the first two chambers, a check valve in said opening to prevent reverse flow therethrough, a fluid passage extending from the upper portion of the body to the lower chamber, and inlet and discharge pipes connected to the fluid and oil passages respectively.

2. In an oil well pump for raising oil from deposits in the earth, a body adapted to be placed in the deposit and having a substantially central longitudinally extending oil passage in the upper portion thereof provided with a flared open lower end, spaced cross walls in the body forming a chamber with which said lower end communicates, another cross wall spaced below the other walls forming

ing a chamber opening through the side walls of the body and a chamber below said wall, a removable closure for the lower end of said body and forming the lower end of said chamber, a separate nozzle extending through and threaded to the two lower cross walls and communicating at its lower end with said lower chamber, said nozzle having a discharge end in the upper chamber directed into the lower open end of the oil passage, the intermediate cross wall having an elongated opening therethrough connecting the first and second chambers, an elongated check valve for controlling said opening to prevent reverse flow therethrough, a motive fluid passage extending longitudinally of the body from the upper portion thereof to said lower chamber, and liquid supply and discharge pipes connected respectively to the motive fluid and oil passages.

3. In an oil well pump for raising oil from deposits in the earth, a body adapted to be placed in the said deposit comprising an elongated substantially cylindrical casing closed at its lower end by a removable closure, said body having means in its upper portion for threaded engagement with two concentric conduits, said body having three substantially transverse walls between the said upper and lower ends forming three chambers, namely an upper chamber, an intermediate chamber and a lower chamber, a substantially central longitudinally extending liquid passage in the upper portion of the body provided with a flared open end and connecting one of the said conduits with the said upper chamber, a fluid passage comprising a nozzle formation directed to discharge into the open end of the said substantially central longitudinally extending liquid passage and extending through the intermediate chamber and forming a communication between the said upper and lower chambers, a cored fluid passage extending longitudinally of the body from the upper end thereof to the said lower chamber, said fluid passage being located independent of and to one side of the said upper and intermediate chambers, a nonreturn valve controlling communication between the upper and intermediate chambers, said intermediate chamber opening through the side of the body to the deposit and encased with a screen, and fluid supply and discharge pipes connected to the upper end of the fluid and liquid passages respectively.

4. In an oil pump for raising oil from deposits in the earth, a body, adapted to be placed in the said deposit, comprising longitudinally extending passages, one of the said passages comprising a venturi with an open end, an inlet passage leading from the deposit to the said open end, a chamber below said inlet passage comprising a removable closure, a second passage extending longitudinally of

the body to the said chamber, said chamber having a removable discharge nozzle leading therefrom and directed to discharge into the said open end of the venturi, and conduits connected to the body and leading from the said passages.

5 In testimony whereof I affix my signature.
WILLIAM F. McMAHON.
